CLAIM

I claim the ornamental design for the supercharger discharge tube, as shown and described.

DESCRIPTION

FIG. 1 is an underside perspective view of a supercharger discharge tube according to the present invention;

FIG. 2 is a left side elevational view of the supercharger discharge tube shown in FIG. 1;

FIG. 3 is a top plan view of the supercharger discharge tube shown in FIG. 1;

FIG. 4 is a rear perspective view of the supercharger discharge tube shown in FIG. 1;

FIG. 5 is a front perspective view of the supercharger discharge tube shown in FIG. 1;

FIG. 6 is a right side elevational view of the supercharger discharge tube shown in FIG. 1; and,

FIG. 7 is a bottom plan view of the supercharger discharge tube shown in FIG. 1.
